UNITED STATES PATENT OFFICE

RUSSELL G. ALLEN, OF TOLEDO, OHIO, ASSIGNOR TO OWENS-ILLINOIS GLASS COMPANY,
OF TOLEDO, OHIO, A CORPORATION OF OHIO

GLASSWARE FORMING MACHINE

Application filed February 18, 1929. Serial No. 340,686.

The present invention relates to improvements in machines for forming hollow glassware, such as bottles and jars, and more particularly to the mechanism by which the article shaping molds are moved between the several positions they assume during production of said glassware.

An important object is to provide novel means whereby the movements of the finishing mold between the blank transfer and article discharging positions may be regulated and controlled with unusual accuracy. To this end there is provided cam actuated differential gearing, which, in the present disclosure, and for the purpose of illustration, replaces the usual serpentine track employed to raise and lower the mold carriers.

Another important object is to provide novel means to prevent premature opening of the finishing mold. Accordingly, the present invention embodies differential gearing for alternately opening and closing the finishing mold in time relation to vertical swinging movement thereof. Operation of this mold opening and closing mechanism is in part controlled by the raising and lowering mechanism and in a manner to prevent premature opening of the mold.

A further object is to provide novel mechanism for adjusting the finishing molds and their carriers vertically relative to the corresponding neck molds and blowing heads. This adjustment permits proper contact between the neck and finishing molds as well as the use of finishing molds of different heights.

Other objects will be apparent hereinafter. In the drawings:

Fig. 1 is a fragmentary sectional elevation 40 of a mold group embodying the present invention.

Fig. 2 is a horizontal sectional view taken substantially along the line II-II of Fig. 1.

Fig. 3 is a vertical sectional view, with 45 parts in elevation, showing the differential gearing employed in opening and closing the mold.

Fig. 4 is a plan view with parts in section, 50 showing the means for actuating the differential gearing.

Fig. 5 is a fragmentary rear elevation showing the mechanism which controls raising and lowering of the mold and opening and closing thereof.

Fig. 6 is a detail vertical sectional view of the differential gear mechanism. 55

Fig. 7 is a diagrammatic illustration of the cams for actuating the mold raising and lowering and mold opening and closing mechanism.

The machine shown in the accompanying drawings and embodying the preferred form of my invention includes a rotary mold carriage 10 about whose periphery is arranged a series of columns or uprights 11 arranged in pairs, each pair adapted to support dipping frames 12. A driving pinion 10^a operates thru a ring gear 11^b to rotate the carriage. Each dipping frame is movable vertically in opposed slideways 13 on said pairs of columns for the purpose of raising and lowering the blank mold (not shown) at regular time intervals during rotation of the carriage 10. The dipping frame 12 is provided with a vertical hinge pin 14 upon which the blowing head 15, blank mold (not shown) and neck mold 15^a are supported. A plunger 16 is supported upon the dipping frame 12 in the usual or any preferred manner. The above structure and operating mechanism therefor are well known and considered not to require further description or illustration. 80

The finishing mold carrier 17 with which the present invention is particularly concerned, is adapted to be moved by differential gearing between blank transfer and article discharging positions. In the present embodiment, the carrier is mounted for vertical swinging movement upon a slide 18 (Figs. 1 and 6) which is substantially inverted U-shaped. An adjustable stop 19^a on one of the slideways 19 in part limits upward swinging movement of the mold carrier. 85

The slide is adjusted vertically in a pair of horizontally spaced slideways 19 suspended from the mold carriage. Vertical adjustment of the slide facilitates changing the spaced relation between the mold carrier 17 and the blowing head 15 and neck mold 15^a so that finishing molds 20 of different heights 100

may be employed, and in addition provides means permitting accurate setting of the finishing mold relative to the blowing head and neck mold. The construction by which 5 said vertical adjustment of the slide 18 is possible, includes a pair of supporting rods 21 (Figs. 1 and 2) secured to the upper end of the slide and threaded thru sleeves 22 rotatably carried by arms 23 which extend forwardly from a cross bar 28 fixed to brackets 29 on the uprights 11. Worm gears 24 (Figs. 1 and 2) on the upper ends of the sleeves 22 run in mesh with worms 25 on a horizontal shaft 26 journaled in bearings 27 on said cross bar 10 28. A hand wheel 30 (Fig. 2) on one end of the horizontal shaft 26 provides means whereby the shaft may be manually rotated when it is desired to rotate the worm gears 24. This 15 operation moves the supporting rods 21 vertically in a direction determined by the direction of rotation of the hand wheel 30. Thus, the elevation of the finishing mold carrier 17 may be easily changed and a nice adjustment 20 obtained.

25 The finishing mold carrier 17 is adapted to be swung vertically about a horizontal axis extending across the slide 18, to thereby move the finishing mold 20 between blank transfer and article discharging positions. According 30 to the present disclosure, such movement of the mold carrier is effected while the mold carriage 10 rotates. Obviously, the principle involved and a major portion of the mechanism may well be embodied in a 35 non-rotating type of machine. In supporting the finishing mold carrier 17 (Fig. 6) so that it may swing vertically, as above stated, arms 17^a are provided at its inner end and are mounted on horizontal co-axial shafts 36 and 38. The shaft 36 extends thru one of the 40 shaft openings 35 and is keyed in an opening 37 in one arm of the slide 18 so that it does not rotate. The finishing mold carrier 17 is adapted to oscillate on this shaft 36 (Fig. 45 6). The other shaft 38 is axially aligned with the shaft 36, but spaced a short distance therefrom, and extends thru the bearing opening 35 in the other arm 17^a and thence into an opening 39 in the adjacent arm of 50 the slide 18. This shaft 38 is keyed in the shaft opening 35 so that it oscillates with the finishing mold carrier 17. Counterweights 40 on said carrier balance the latter to a greater or less extent on the supporting shafts 36 55 and 38 and thereby minimize the strain on the lifting and lowering mechanism to be now described.

Mechanism for alternately raising and lowering the finishing mold carrier 17 (Figs. 60 4, 5 and 6) includes cam actuated differential gearing which is in part arranged between the adjacent ends of the shafts 36 and 38. This differential gearing includes a housing H comprising a pair of end plates 45 rotatably mounted on adjacent ends of the 65 shafts 36 and 38 and connected together by side walls 46. A pair of shafts 47 extend inwardly from opposite sides of the housing and carry pinions 48. These pinions 48 run in mesh with a pair of bevel gears 49 or pinions which are arranged between the end plates 45 and keyed to reduced extensions 50 on the shafts 36 and 38. The end plate 45 which is journaled upon the shaft 36 (Fig. 6) carries a bevel gear segment 51 running in 70 mesh with a pinion 52 at the upper end of a shaft 53 journaled in a bearing 54 on one arm of the slide 18. The lower end of the shaft 53 is journaled in a bearing 55 on one of the guide members 19, said bearing comprising a pair of vertically spaced arms between which a spur gear 56 is disposed. This spur gear is splined to the shaft 53 to allow vertical adjustment of the slide 18 relative to the bearing 55 without interfering with 75 the driving connection between said gear 56 and the remaining mechanism. A rack bar 57 (Figs. 4, 5 and 6) runs in mesh with the gear or pinion 56 and extends horizontally 80 inward thru a guideway 58. A slide block 59 is connected to the inner end of the rack bar and carries a cam roll 60 which runs in a continuous cam 61, the latter being shaped to 85 impart a reciprocating movement to the rack bar at proper time intervals. A yielding connection 162 is provided between the rack bar 57 and slide block 59 as a precaution against breaking or undue straining of the mechanisms in the event abnormal conditions arise.

At a predetermined point in the closed path 90 followed by the finishing mold carrier 17, the rack bar 57 (Fig. 4) is moved radially inward by means of an angular portion 62 in the cam 61. This movement of the rack bar rotates the gear 56 which in turn imparts 95 rotary movement to the shaft 53 and pinion 52. The pinion 52 rotates the gear segment 51 and thru the pinions 48 imparts rotary movement to the gear or pinion 49 carried by the shaft 38. In this manner the mold carrier 17 is swung downwardly from a blank transfer position to an article discharging position. The mold carrier is returned to its horizontal or blank transfer position by reversing the rotation of the gear 56, such reversal being caused by the cam roll 60 moving thru the angular portion 62^a of the cam 61 100 (Fig. 7). The differential gearing provides means whereby the mold carrier 17 moves about its axis twice the angular distance traveled by the gear housing H. Thus, for example, the housing H need only be moved thru an angle of 30° in order to obtain a 60° movement of the mold carrier 17.

Cooling air for application to the outer 105 walls of the mold 20 is delivered to the hollow arms 65 by way of passageways 100 in the arms 17^a (Fig. 6), ports 101 in the side members of the slide 18 and chambers 102 in the slideways 19. These chambers 102 may com- 110

115

130

municate with any suitable source of supply for cooling air.

The finishing mold 20 (Figs. 1 and 3) may be opened at any time regardless of the raising and lowering movements of the mold carrier 17. The cam formation controls this operation and determines where the mold opens. Also the mold opening and closing mechanism is such that it positively prevents premature opening of the mold. Accordingly, formation of distorted glassware insofar as premature opening of the finishing molds is concerned may be avoided. The mold opening and closing mechanism includes a pair of mold arms 65 (Fig. 2) fulcrumed to a vertical hinge pin 66 on the mold carrier 17 and connected at their outer ends thru links 67 to the free ends of the sections of the finishing mold 20. The inner ends of the mold arms 65 are connected thru links 68 to a slide block 69 (Figs. 2, 5 and 6). This slide block is arranged in a guideway 70 in the mold carrier 17. A rack bar 71 is formed on the lower side of the slide block 69 and runs in mesh with an idler gear 72 carried by a shaft 73 journaled in bearings 74 on the lower side of the mold carrier 17. This idler gear 72 is actuated by differential gearing which is carried in part by the shaft 38.

This differential gearing (Figs. 2, 3 and 5) includes a combined bevel and spur gear 75 rotatably carried by said shaft 38 and positioned so that it abuts the adjacent end plate 45 of the previously mentioned differential housing H. The teeth on the periphery of the gear 75 run in mesh with the idler gear 72. The bevel gear teeth 76 constantly mesh with a pinion 77. This pinion 77 is carried by an arm 78 fixed to the aforementioned differential housing H and extending horizontally therefrom. A double bevel gear 79 (Figs. 5 and 6) is rotatably mounted on the shaft 38 and spaced from the gear 75 by a collar 80. One series of teeth on the gear 79 runs in mesh with the aforementioned pinion 77 while the other teeth are constantly in mesh with a driving pinion 81 at the upper end of a vertical shaft 82. This shaft is journaled in vertically spaced bearings 83. The lower bearing 83 is bifurcated and its arms embrace a spur gear 84 splined to the shaft 82 and running in mesh with a rack bar 85. This rack bar 85 (Figs. 4, 5 and 6) is yieldingly connected thru a spring device 87 to a slide block 88 which carries a cam roll 89 running in a continuous stationary cam 90. This cam 90 (Fig. 4) is formed with an angular portion 91 located at any predetermined position regardless of the location of the angular portion 62 in the cam 61, to effect opening or closing of the mold at any desired point.

When the mold is to be opened the shaft 82 (Figs. 4, 5 and 6) is rotated to thereby impart rotary movement to the double bevel

gear 79 and thence by way of the pinion 77 to the combined bevel and spur gear 75 which runs in mesh with the idler gear 72. During the mold opening operation the pinion 77 (Fig. 5) is rotated counterclockwise and thru the gears 75 and 72 moves the slide block 69 radially inward. Such movement of the slide block in turn moves the outer ends of the mold arms 65 away from each other and thereby separates the mold halves. The relative positions of the angular portions 62 and 91 of the cams and the pitch thereof predetermine the point at which the mold opens relative to its downward swing, and the speed at which the mold is lowered and opened, respectively. This may be varied as required by different operating conditions.

The opening and closing movements of the mold 20 are dependent entirely on rotation of the shaft 82 actuated by the rack and pinion 85, 84 under the control of the cam 90, said shaft 82 operating in turn thru the gear train including (see Fig. 5) pinion 81, double gear 79, gears 77, 75, idler gear 72 (Fig. 3) and rack 71. While the shaft 82 is not rotating there is no opening or closing movement of the mold, even when the mold frame is being lifted or lowered, notwithstanding the fact that certain gears of said gear train, including gears 77 and 75 are rotated during the swinging movement of the mold frame. The reason for this will be apparent from the following considerations:

By reference to Fig. 3, it will be observed that during the downward swing, for example, of the mold frame 17, the gear 75 must rotate with the frame about the axis of the shaft 38 and at the same angular speed as the mold frame to prevent operation of the slide block 69. In other words, there must be no relative movement of the frame 17 and gear 75. The required rotation is imparted to the gear 75 at this time by the pinion 77 (see Fig. 5) carried on the gear casing H which, as hereinbefore explained rotates about the axis of the mold frame as the latter swings down. As the gear 77 is in mesh with the now stationary gear 79 and rolls thereon it will rotate the gear 75 at double the angular speed with which the gear casing H is rotating about its axis. But as said gear casing rotates in the same direction and at only half the speed of the mold frame, as hereinbefore explained, the gear 75 will evidently rotate at the same speed as the mold frame 17. Thus, as above noted, no opening or closing movement is imparted to the mold by the swinging of the mold frame. Premature opening of the mold as it swings downward to a discharging position is thus prevented.

When the mold reaches the point at which it is to be opened, the angular portion 91 in the cam 90 (Fig. 4) suddenly imparts such

a degree of rotation to the pinion 81 and double bevel gear 79 (Fig. 5) that the speed of rotation of the pinion 77 is increased and operates thru the gears 75 and 72 to move the slide block 69 radially inward. The mold arms 65 (Fig. 2) are opened by said movement of the slide block 69 and in turn separate the sections of the mold 20. When the cam roll 89 reaches the angular portion 91* in the cam 90 a reverse movement is given the rack bar 85 to thereby actuate the mold closing mechanism.

Modifications may be resorted to within the spirit and scope of my invention.

15 What I claim is:

1. In a glass forming machine, the combination of a mold carrier mounted to swing up and down about a horizontal axis, a partible mold on said carrier, means for swinging said carrier about said axis for raising and lowering the mold, mechanism for opening and closing the mold including a gear train, said train comprising a gear rotatable about said horizontal axis, and means cooperating with said carrier swinging means for causing said gear to rotate about said axis with the mold carrier and at the same angular velocity during said raising and lowering of the mold, whereby the swinging of the mold carrier about said axis will not cause opening or closing movements of the mold.

2. In combination, a mold carrier support, a pair of horizontally aligned shafts on the support, a mold carrier mounted on the shafts, a partible mold on the carrier, differential gearing carried by the shafts, actuating means operating through said gearing for moving the carrier about the common axis of the shafts, means to alternately open and close the mold, said mold opening and closing means including a gear carried by one of the shafts, and means whereby operation of said differential gearing causes said last mentioned gear to rotate with the mold carrier about said axis and thereby prevent opening and closing the mold independently of said mold opening and closing means.

3. In combination, a support, a mold carrier fulcrumed thereto, a partible mold on said carrier, means to swing the carrier about its fulcrum, automatic cam actuated gearing arranged to alternately open and close the mold, said gearing operable to effect opening and closing movements of the mold independently of the position to which the carrier has been swung about its said fulcrum, and a cam for actuating the gearing at regular time intervals.

4. In combination, a mold carrier, a partible mold thereon, a support for the mold carrier including a non-rotating shaft, and a rotary shaft spaced from and axially aligned with the other shaft, said mold carrier fixed to the rotary shaft and loosely mounted on the non-rotating shaft, a driven gear fixed to

the rotary shaft, a driving gear conaxial with said driven gear, means for periodically oscillating the driving gear, and driving connections between said gears whereby the driven gear is operated by and at a greater 70 angular speed than the driving gear.

5. In combination, a mold carrier, a partible mold thereon, a support for the mold carrier including a non-rotating shaft and a rotary shaft spaced from and axially aligned 75 with the other shaft, said carrier being fixed to the rotary shaft and loosely mounted on the non-rotating shaft, a driven gear secured to the rotary shaft, a driving gear conaxial with said driven gear, means for oscillating 80 the driving gear at regular time intervals, driving connection between said gears whereby the driven gear is operated by and at substantially twice the angular speed of the driving gear, means for opening the mold, 85 and means controlled by said driving connection between the gears for securing the mold against premature opening.

6. In combination, a mold carrier, a partible mold thereon, gear mechanism for alternately opening and closing the mold, a mold carrier support including a non-rotating shaft and a rotary shaft spaced from and axially aligned with the other shaft, said carrier being fixed to the rotary shaft and 90 loosely mounted on the non-rotating shaft, additional gear mechanism in part carried by and interposed between the adjacent ends of said shafts for oscillating the rotary shaft and thereby imparting corresponding movement to the mold carrier, and means controlled by operation of said additional gear mechanism for holding the mold against 95 premature opening.

7. In a glass forming machine, the combination of a rotating mold carriage, a mold carrier mounted thereon to swing up and down about a horizontal axis, a partible mold on said carrier, a stationary cam, means actuated by the cam for swinging said carrier about said axis and thereby raising and lowering the mold, mechanism for opening and closing the mold including a stationary cam and a gear train actuated by the cam, said train comprising a gear rotatable about said horizontal axis, and means cooperating with said carrier swinging means for causing said gear to rotate about said axis with the mold carrier and at the same angular velocity during said raising and lowering of the mold, whereby the swinging of the mold carrier about said axis will not cause opening or closing movements of the mold.

Signed at Toledo, Ohio, this 15th day of February, 1929.

RUSSELL G. ALLEN.
